UNITED STATES PATENT OFFICE.

LOUIS SAMETZ, OF BROOKLYN, NEW YORK.

POWER-PRESS.

1,390,589.

Specification of Letters Patent. Patented Sept. 13, 1921.

Application filed October 7, 1920. Serial No. 415,297.

To all whom it may concern:

Be it known that I, LOUIS SAMETZ, a citizen of the United States, residing at Brooklyn, in the county of Kings and State of New York, have invented certain new and useful Improvements in Power-Presses; and I do hereby declare the following to be a full, clear and exact description of the invention, such as will enable others skilled 10 in the art to which it appertains to make and use the same, reference being had to the accompanying drawings, and to characters of reference marked thereon, which form a part of this specification.

The present invention relates, generally, to improvements in power presses; and the invention has reference, more particularly, to an improved construction of power press for molding and shaping plastic material, such, 20 for example, as celluloid, etc.

The invention has for its principal object to provide a press for operating male and female shaping dies, under proper timed control whereby the dies are automatically 25 held under adequate pressure in mutual cooperation for a desired period of time, and then separated for the removal of the article formed thereby.

Another object of the invention is to provide a novel means for reciprocating one of the dies in combination with a positive automatic means for forcing the dies apart when separating or opening the same for the removal of the article formed thereby.

Other objects of the present invention, not at this time more particularly enumerated, will be clearly understood from the following detailed description of the same.

With the various objects of the present invention in view, the same consists, primarily, in the novel construction of reciprocating power press hereinafter set forth; and, the invention consists, furthermore, in the novel arrangements and combinations 45 of the various devices and parts, as well as in the details of the construction of the same, all of which will hereinafter more fully described, and then finally embodied in the claims appended hereto.

The invention is clearly illustrated in the accompanying drawings, in which:

Figure 1 is a side elevation of the novel construction of press made according to and embodying the principles of the present invention; Fig. 2 is a front elevation of the same; Fig. 3 is a transverse vertical section

through the same, taken on line 3—3 in said Fig. 1; Fig. 4 is a detail horizontal section, taken on line 4—4 in said Fig. 1; and Fig. 5 is a detail view illustrating the operation 60 of the mechanism designed to positively actuate the separation of the dies operated by the press.

Similar characters of reference are employed in all of the hereinabove described 65 views, to indicate corresponding parts.

Referring now to said drawings, the reference character 1 indicates a suitable base-plate or bed upon which the press is mounted. Fixed upon said base plate or bed 1 70 are a pair of side frames or standards 2 upon and by which the moving parts of the press mechanism are supported. Secured to said side frames or standards at their front ends, and so as to extend between the 75 same, is a front plate 3 provided with suitably formed vertical guideway members 4, between which is guided, for vertical reciprocatory movement, a cross-head plate 5, to the lower end of which is fixed a male die 80 member 6. Said cross head plate is provided with bearing portions 7 for supporting a transverse wrist pin 8 to which is pivotally connected the lower end of a connecting rod 9.

Mounted in bearing portions 10 formed in the upper portions of said side frames or standards 2 is a transverse rock-shaft 11 upon which is fixed a lever member 12, the forward end of which is provided with a 90 bifurcated portion or fork 13 in which is supported a wrist pin 14 to which is pivotally secured the upper end of said connecting rod 9. The rearward end of said lever member 12 is provided with a similar bifurcated portion 15 for journaling an axle pin 16 upon which is rotatably mounted an anti-friction roller 17.

Formed in the upper portions of the rearward ends of said side frames or standards 100 2 are bearing members 18, in which is journaled a transverse cam shaft 19. Fixed on said cam-shaft 19 is a cam member 20, upon the periphery of which rides the anti-friction roller 17 of said lever member 12. 105 The means for maintaining the lever member 12 under such control as to assure the riding contact of its anti-friction roller 17 with the periphery of said cam member 20, comprises a rearwardly projecting arm 21 110 which is fixed on said rock-shaft 11, and which is provided adjacent to its free end

with a weight 22. The pull of gravity on the weight 22 tends to normally swing downward the arm 21 whereby the rock-shaft normally tends to rotate in such direction as to swing the rear end of said lever member 12 downward, so as to press said anti-friction roller 17 in constant engagement with the periphery of said cam member 20.

10 The transmission means for driving said cam-shaft 19 comprises a stud-shaft 23 which projects outwardly from one of said side frames or standards 2, and upon which is mounted a loose pulley 24 adapted to be 15 driven by a belt (not shown). Slidably mounted on said stud-shaft 23 is a rotatable clutch-sleeve 25, from the outer face or end of which project clutch pins 26, which, when said clutch-sleeve is moved toward the pulley 24, are engageable in clutch sockets 27 connected with said pulley, so that the rotary motion of said pulley is transmitted to said clutch-sleeve. Fixed on the inner end of 20 said clutch-sleeve 25 is a pinion 28, which 25 rotates with said clutch-sleeve. Said side frame or standard 2 which is provided with the stud-shaft 23 is also provided with an additional bearing member 29 in which is journaled an intermediate shaft 30. Fixed 30 on the outer end of said shaft 30 is a gear wheel 31 which meshes with and is driven by said pinion 28, and fixed on the inner end of said shaft 30 is a pinion 32. Fixed 35 on said cam shaft 19 is a gear wheel 33 which meshes with and is driven by said pinion 32.

The means for operating the clutch-sleeve 25, and automatically releasing the same to stop the rotation of the cam member 20 40 when the same completes a revolution, comprising a transverse shift-bar 34 which is mounted for longitudinal movement in bearing or guide openings 35 provided in said side frames or standards 2, so as to be disposed parallel to and forward of said cam-shaft 19. Said shift-bar 34 is provided at one end with a yoke-arm 36 having a fork-portion or yoke 37 which embraces said clutch-sleeve in an annular groove or channel 38 formed in the latter. Said shift-bar 34 is normally moved or shifted from right to left by means of a compression spring 39 which is arranged between a side frame or standard 2 and a collar 40 fixed upon said shift-bar. The normal sliding movement of 45 said shift-bar, as actuated by the spring 39 tends to slide said clutch sleeve 25 into operative clutched relation to the driving pulley 24. Normally said shift-bar is held in re- 50 tracted position, against the tension of said spring 39, and so as to hold the clutch-sleeve in released position, by means of a pivoted stop-lever 41 which is mounted upon the exterior side of the right hand side frame or 55 standard 2, said stop-lever 41 normally en-

gaging a stop-collar 42 fixed on the outer right hand end of said shift-bar. Said stop-lever is normally maintained in and returned to operative position relative to said stop collar 42 by means of a pull spring 41' which tends to constantly move or swing the stop-lever downwardly toward the shift-bar. Said stop-lever is provided with an upturned handle portion 43 at its forward end for manipulating the same. 75

When it is desired to start the operation of the machine by throwing in the clutch mechanism, the stop-lever 41 is swung upwardly by pulling forward the handle portion 43, thus disengaging the same from the stop collar 42, whereupon the spring 39 will cause the shift-bar to move from right to left and thereby move the clutch-sleeve 25 into clutched relation to the pulley 24. Upon this occurrence the movement of the pulley 24 will be transmitted to the clutch-sleeve and its pinion 28, and thence through the gear 31, intermediate shaft 30, pinion 32 and gear 33 to the cam shaft 19, thus rotating the latter and causing the operative rotation of the cam member 20. Since it is desirable that the machine be automatically stopped when the cam member 20 completes one revolution, the following means is provided for accomplishing such result. Mounted on the side or inner face of said gear 33 is a cam projection 44, and fixed on said shift bar 34 is a retractor arm 45 which projects outwardly from the shift bar 34 toward the cam-shaft 19. When said shift bar moves to clutch throwing position, said retractor arm 45 shifts to a position disposing the same in the path of rotation or movement of said cam projection 44. As the cam shaft 19 approaches the completion of one revolution, the cam projection 44 is carried around by the gear 33 into operative engagement with said retractor arm 45, whereby the latter is pushed back, and thereby causes a retractive movement of the shift bar 34. When the shift bar 34 has been retracted to normal initial position, not only has the clutch-sleeve 25 been released from clutched engagement with the pulley 24 so that the transmission mechanism 100 is stopped and the cam-shaft 19 and its cam member 20 brought to rest upon the completion of a single revolution of the latter, but the stop-collar 42 is also carried outwardly so that the actuating spring 41' may again swing downwardly the stop lever 41 behind the stop collar 42, thus again holding the shift bar against the clutch operating movement and thus bringing the machine to rest with all its mechanisms in normal initial or starting positions. 115

Fixed on the base plate or bed 1 is a stationary female die 46 with which the vertically reciprocated male die 6 cooperates.

In operation, when the machine is at rest, the material to be molded or shaped by the 120

dies 6 and 46, is placed in the female die 46. The machine is then put in motion so that power is transmitted to the cam shaft, as above described, whereupon the cam member 20 is rotated. The periphery of said cam member is shaped to provide a lifting portion 47, a concentric dwelling portion 48, and a descending portion 49. As the cam shaft begins its rotation the lifting portion 47 of the cam member is carried against the anti-friction roller 17 of the lever member 12, causing the roller to ride upwardly thereupon and into engagement with the dwelling portion 48, 5 thereby rocking the lever member 12 so as to impart to the cross head plate 5 a downward movement which carries the male die 6 into coöperative relation to the female die 46 and the material to be molded or shaped. 10 As the cam member continues to rotate, the roller 17 rides upon the concentric dwelling portion 48 of the cam member, thus serving to hold the dies 6 and 46 in desired mutual or coöperating relation for a fixed period 15 of time sufficient to permit the material to be molded or shaped to set in the shape or form impressed thereupon by the said dies. The period of time during which the dies are thus held in mutual coöperative relation may 20 be varied as desired, either by varying the speed of rotation of the shaft by altering the gearing relations of the transmission mechanism, or by shortening or lengthening the arc of the dwelling portion 48 of the cam 25 portion 20. Said dwelling portion 48 of the cam member 20 terminates in the descending portion 49, so that as the cam member 20 approaches the end of a revolution the roller 17 will descend said descending portion 30 thus permitting the lever member 12 to rock back to normal position, whereby the male die is returned to normal raised position by the time a single revolution of the cam is completed, and the rotation of the cam is 35 thereupon stopped by the operation of the clutch shift bar mechanism above described. By reason of the fact that the male die 6, when free to rise, may tend to cleave to the molded or shaped material, so that the weight 40 22, which slightly overbalances the weight of the cross-head plate and die 6, may not be sufficient to overcome such adherence, it is desirable to provide a means for positively producing an initial separation of the 45 male die 6 from the female die 46. The means serving such purpose comprises a lever device 50 which is fixed to said rock-shaft 11 so as to depend therefrom, and which is provided with a rearwardly projecting integral arm 51 at its free end having a laterally off-set socket portion or perforate ear 52 in which is secured the shank 53 of a concave lip piece 54. Pivotally mounted upon a fulcrum stud 55 which 55 projects from one side of said cam-member 60 20 is a trip member 56. A coil spring 57 having one end secured to said cam member and the opposite end secured to said trip member 56, tends to normally maintain the latter in a position stopped against the hub 70 of said cam member, as shown in Fig. 1 of the drawings. When the lever member 12 is moved to operated position to cause the coöperation of the dies 6 and 46, the oscillation of rock-shaft 11 swings said lever device 50 rearwardly so that the lip piece 54 is positioned in the path of the nosing or free end 58 of said trip member 56. As the cam-member 20 rotates said trip member 56 is carried around until by the time 75 the roller 17 of the lever member 12 rides upon the descending portion 49, said nosing or free end 58 of the trip member is moved into engagement with the lip piece 54. Continued rotation of the cam member 20 causes 80 said trip member to push upon the lever device 50, the trip member being free to turn upon its fulcrum stud 55. In this manner a positive pressure is applied to said lever device 50 which swings the same forward and thereby rocks said rock-shaft in the reverse direction to produce a positive lifting movement of the lever member 12 relative to the cross-head plate 5 and die 6 carried thereby, so that the die 6 is positively forced apart or separated from the material molded or shaped by the coöperative action of the latter with the die 46. Immediately before the cam-member 20 completes its rotation the trip-member 56 100 frees itself from the lip piece 54, so that the spring 57 returns said trip member to normal initial position. In the meantime the die 6 having been forcibly separated from the molded or shaped material, the pull of 105 gravity upon the weight 22 is sufficient to continue the returning movement of the rock shaft 11 and parts mounted thereon to normal initial position, as will be clearly understood. 110

From the above description it will be very apparent that the construction of press involves a novel combination of means for producing a timed coöperation of the molding dies under adequate pressure assuring 115 the proper functioning of the same, together with means for positively actuating the separating movements of the dies.

I am aware that some changes may be made in the arrangements and combinations 120 of the various devices and parts, as well as in the details of the construction of the same, without departing from the scope of my present invention as set forth in the foregoing specification and as defined in the appended claims. Hence, I do not limit my invention to the exact arrangements and combinations of the various devices and parts described in said specification, nor do I confine myself to the exact details of the 125 130

construction of the said parts as illustrated in the accompanying drawings.

I claim:

1. In a device of the kind described, a pair of dies, means for mounting one die for vertical reciprocating movement, a rocking lever for actuating said movable die, a secondary lever device movable with said rocking lever, a cam for actuating said rocking lever in one direction to produce the operative stroke of said movable die, and means coöperating with said secondary lever device for actuating said rocking lever in the opposite direction to positively and forcibly initiate a separation of said movable die from the work after operation. 70
2. In a device of the kind described, a fixed die, a supporting frame work, a vertically movable die supported by said frame work for coöperation with said fixed die, a rocking lever for actuating said movable die, a rotary cam having a concentric dwelling portion for actuating said rocking lever, a transmission means for rotating said cam, means for automatically stopping said cam upon the completion of a single revolution, and means for positively initiating the reverse movement of said rocking lever to force the movable die from coöperative relation with said opposite die, comprising a lever device in fixed relation to said rocking lever, and a pivoted spring retained trip member carried by said cam to engage and operate said lever device. 85
3. In a device of the kind described, a base, a frame work mounted on said base, a vertically reciprocable cross-head plate mounted on said frame work, a movable die carried by said cross-head plate, a fixed die mounted on said base with which said movable die coöperates, a rock shaft journaled in said frame work, a lever member fixed on said rock shaft, a connecting rod joining the forward end of said lever member with said cross-head plate, a cam shaft journaled in said frame work, a cam having a lifting portion, a concentric dwelling portion and a descending portion at its periphery, said cam being adapted to operatively engage the rear end of said lever member, means for counterbalancing said lever member against the weight of said cross-head plate and its die, a stud shaft connected with said frame work, a power driven pulley journaled on said stud shaft, a clutch sleeve having a pinion slidable on said stud shaft, intermediate gear transmission means driven by said pinion to rotate said cam shaft, spring actuated means for moving said clutch sleeve into clutched relation to said pulley, 90 manually controlled stop means for holding said clutch sleeve operating means inactive, and means for automatically returning said clutch sleeve operating means to clutch releasing normal initial position upon the completion of a single revolution of said cam, a second lever device fixed on said rock shaft, and a pivoted spring retained trip member carried by said cam to engage and operate said lever device to positively initiate a reverse movement of said rock shaft and parts connected therewith when said descending portion of said cam rides into engagement with the rear ends of said lever member. 95
4. In a device of the kind described, a base, a frame work mounted on said base, a vertically reciprocable cross-head plate mounted on said frame work, a movable die carried by said cross-head plate, a fixed die mounted on said base with which said movable die coöperates, a rock shaft journaled in said frame work, a lever member fixed on said rock shaft, a connecting rod joining the forward end of said lever member with said cross-head plate, a cam shaft journaled in said frame work, a cam having a lifting portion, a concentric dwelling portion and a descending portion at its periphery, said cam being adapted to operatively engage the rear end of said lever member, means for counterbalancing said lever member against the weight of said cross-head plate and its die, transmission means for rotating said cam, means for automatically stopping said cam upon the completion of a single revolution, a second lever device fixed on said rock shaft, and a pivoted spring retained trip member carried by said cam to engage and operate said lever device to positively initiate a reverse movement of said rock shaft and parts connected therewith when said descending portion of said cam rides into engagement with the rear ends of said lever member. 100
5. In a device of the kind described, a pivoted lever member for actuating a vertically movable die, a cam shaft, and a cam having a lifting portion, a concentric dwelling portion and a descending portion at its periphery, said cam being adapted to engage the rear end of said lever member to operate the same, a power transmitting pulley, transmission means intermediate said pulley and said cam shaft, said transmission means including a clutch, means for actuating said clutch, manually controlled stop means for normally holding said clutch actuating means in clutch releasing position, and means for automatically returning said clutch actuating means to clutch releasing position upon the completion of a single revolution of said cam. 110
6. In a device of the kind described, a pivoted lever member for actuating a vertically movable die, a cam shaft, a cam having a lifting portion, a concentric dwelling portion and a descending portion at its periphery, said cam being adapted to engage the rear end of said lever member to operate 115
7. In a device of the kind described, a pivoted lever member for actuating a vertically movable die, a cam shaft, a cam having a lifting portion, a concentric dwelling portion and a descending portion at its periphery, said cam being adapted to engage the rear end of said lever member to operate 120
8. In a device of the kind described, a pivoted lever member for actuating a vertically movable die, a cam shaft, a cam having a lifting portion, a concentric dwelling portion and a descending portion at its periphery, said cam being adapted to engage the rear end of said lever member to operate 125
9. In a device of the kind described, a pivoted lever member for actuating a vertically movable die, a cam shaft, a cam having a lifting portion, a concentric dwelling portion and a descending portion at its periphery, said cam being adapted to engage the rear end of said lever member to operate 130

- the same, a power transmitting pulley, transmission means intermediate said pulley and said cam shaft, said transmission means including a clutch, means for actuating said clutch, manually controlled stop means for normally holding said clutch actuating means in clutch releasing position, means for automatically returning said clutch actuating means to clutch releasing position 5
- 10 upon the completion of a single revolution of said cam, a second lever device in fixed relation to said lever member, and a pivoted spring retained trip member carried by said cam to engage and operate said lever device
- 15 to positively initiate a reverse movement of said lever member for forcibly retracting said movable die when said descending portion of said cam rides into engagement with said lever member.
- 20 7. In a device of the kind described, a pivoted lever member for actuating a vertically movable die, a rotary cam means engageable with the rear end of said lever member to produce the operative stroke of 25 the latter, means for normally maintaining the rear end of said lever member in riding engagement with said cam means, and means for positively and forcibly initiating the return stroke of said lever member.
- 30 8. In a device of the kind described, a pivoted lever member for actuating a vertically movable die, a rotary cam means engageable with the rear end of said lever member to produce the operative stroke of 35 the latter, means for normally maintaining the rear end of said lever member in riding engagement with said cam means, and means for positively and forcibly initiating the return stroke of said lever member, comprising a second lever device in fixed relation to said lever member, and a pivoted spring positioned trip member carried by
- 40 said cam means to engage and operate said lever device as said cam means approaches the completion of its rotary movement. 45
9. In a device of the kind described, a pivoted lever member for actuating a vertically movable die, a cam means having a lifting portion, a dwelling portion and a descending portion, said cam means being engageable with the rear end of said lever member to produce the operative stroke of the latter, means for normally maintaining the rear end of said lever member in riding engagement with said cam means, and 50 means for positively and forcibly initiating the return stroke of said lever member.
10. In a device of the kind described, a pivoted lever member for actuating a vertically movable die, a cam means having a lifting portion, a dwelling portion and a descending portion, said cam means being engageable with the rear end of said lever member to produce the operative stroke of the latter, means for normally maintaining 55 the rear end of said lever member in riding engagement with said cam means, a second lever device in fixed relation to said lever member, and a pivoted spring retained trip member carried by said cam to engage and 60 operate said lever device to positively initiate a reverse movement of said lever member for forcibly retracting said movable die when said descending portion of said cam rides into engagement with said lever member. 65
- 70
- 75
- In testimony, that I claim the invention set forth above I have hereunto set my hand this 29th day of September, 1920.
